UNITED STATES PATENT OFFICE.

CALVIN C. MILLER, OF SUMMITHILL, PENNSYLVANIA.

FIGURE TOY.

1,257,093.

Specification of Letters Patent. Patented Feb. 19, 1918.

Application filed August 10, 1916. Serial No. 114,221.

To all whom it may concern:

Be it known that I, CALVIN C. MILLER, a citizen of the United States, residing at Summithill, in the county of Carbon and State of Pennsylvania, have invented certain new and useful Improvements in Figure Toys, of which the following is a specification.

This invention relates broadly to toys, and 10 more particularly to a figure toy.

As the primary object, this invention contemplates the provision of a toy embodying a movable figure arranged over a wash tub, the figure having pivotally connected arms 15 which move up and down the washboard imitating a person washing clothes.

It is another object of this invention to provide novel means for connecting the two sections of the figure in order that the body 20 portion which has the arms connected thereto, will rock back and forth so that the arms will be moved up and down the washboard.

It is a more specific object of this invention to provide friction means for actuating 25 the figure; and to otherwise improve the construction and arrangement of parts so that when assembled they will efficiently actuate.

A still further object of my invention resides in the provision of a device of the character described that is simple in construction, 30 efficient in operation and one that can be manufactured and placed on the market at a minimum cost.

Other objects as well as the nature, 35 characteristic features and scope of my invention will be more readily understood from the following description taken in connection with the accompanying drawings and pointed out in the claims forming a part of this 40 specification.

In the drawings:—

Figure 1 is a side elevation of my invention showing particularly the operating means.

Fig. 2 is also a side elevation of my invention illustrating to advantage the means for connecting the sections of the figure.

Fig. 3 is a rear elevation of my invention.

Referring more particularly to the drawings in which similar reference numerals 50 designate like and corresponding parts throughout the different views, I provide a base 1 on which is mounted adjacent one end thereof a supporting bench 2. A miniature wash tub 3 is connected to the bench and supported by the latter and also has a minia-

ture washboard 4 arranged against the side as illustrated to advantage in the accompanying drawings.

Also mounted on the upper surface of the 60 base and positioned adjacent the washboard is a figure composed of a vertical supporting section 5 and a body section 6 having a rounded lower edge 7 which is receivable within the recess 8 in the upper surface of 65 the section 5. Brackets 9 are rigidly connected to the respective sides of the stationary section. An arm 10 is rigidly connected through the medium of a suitable securing element 11 to the lower side of the body section 6 while the inner end of the arm is bent at right angles and is passed through the alining openings in the upper ends of the bracket 9 and the body section 6 as indicated by the numeral 12. By this arrangement it 70 is apparent that the body section 6 is movable with respect to the stationary supporting section 5. Arms 13 are pivotally connected to the sides of the body section 6 adjacent the head 14 while a block 15 is pivotally mounted between the hands 16. This block represents a piece of cloth that is being washed and is adapted to lie upon the washboard as are the arms.

In order to actuate the toy I have provided 85 a connecting rod 17 the upper end of which is looped as at 18 and pivotally connected thereby to another loop 19 formed on the outer end of the arm 10. The opposite end of the connecting rod is looped as at 20 and 90 loosely arranged about the crank portion 21 of the shaft 22, the latter being rotatably mounted in the stationary section 5. A friction wheel 23 is preferably rigidly mounted on the opposite projecting end of the shaft 95 and is frictionally engaged by another shaft 24 the respective ends of which are rotatably mounted on the section 5 of the figure and on the vertical standard 25 secured as at 26 to one side of the base. A large wheel 27 100 which serves as a weight is carried by the shaft 24 intermediate its ends so as to weight the shaft 24 and thereby increases frictional engagement of the frictional wheel 23 and the shaft 24.

The operation of my invention is as follows:—

A string (not shown) is preferably wound about the shaft 24 and as it is unwound therefrom the shaft will be rotated. Because of the frictional engagement of this shaft with the wheel 23 the latter will be 110

rotated and will consequently actuate the crank shaft 21. As the connecting rod 17 is connected to the crank shaft 21 and to the arm 10 which latter is in turn rigid with the body section, the said body section will be rocked back and forth and simultaneously with this movement the pivoted arms 13 will move the block 15 up and down the washboard.

10 Although I have shown and described the preferred embodiment of my invention I desire it to be understood that I am not to be limited to the exact details shown, however, I desire that great stress be laid upon the arrangement of the figure toy which imitates a person washing clothes over the wash tub. Attention is also directed to the arrangement of the means for moving one section relative to the other and consequently 15 cause the arm to move up and down the washboard. Incidentally at this point, it may also be stated that other means may be employed for moving the figure.

From the above description taken in connection with the accompanying drawings, it 25 can easily be seen that I have provided a device that is simple in construction, containing but a few simple parts that can be cheaply manufactured and assembled and 30 when assembled can be placed upon the market and sold at a minimum cost.

It will be understood that the above description and accompanying drawings comprehend only the general embodiment of my 35 invention and that various minor changes in detail of construction, proportion and arrangement of the parts may be made within the scope of the appended claims and without sacrificing any of the advantages of my 40 invention.

Having thus fully described my invention, what I claim as new and desire to secure by Letters Patent, is:—

45 1. A toy figure including a base, a receptacle thereon, a wash board in the receptacle,

Copies of this patent may be obtained for five cents each, by addressing the "Commissioner of Patents, Washington, D. C."

a sectional figure consisting of a stationary lower portion, mounted on the base and having the upper end thereof formed with a concaved recess, said figure further consisting of an upper body portion having a convexed lower end fittedly disposed in said concaved recess, means for pivotally securing the upper portion to the lower stationary portion whereby the upper portion may oscillate in said concaved recess, arms pivoted to said body portion of the figure and adapted to rest on said wash-board, a rigid arm secured to the body portion, a crank shaft journaled in the stationary portion, a wheel mounted on said shaft, and a link connecting said crank shaft with said rigid arm.

2. A toy including a base, a receptacle thereon, a wash-board in the receptacle, a sectional figure consisting of a stationary lower portion mounted on the base and having the upper end thereof formed with a concaved recess, said figure further consisting of an upper body portion having a convexed lower end fittedly disposed in said concaved recess, means for pivotally securing the upper portion to the lower stationary portion whereby the upper portion may oscillate in said concaved recess, arms pivoted to said body portion of the figure and adapted to rest on said wash-board, a rigid arm secured to the body portion, a crank shaft journaled in the stationary portion, a wheel mounted on said shaft, and a link connecting said crank shaft with said rigid arm, and a momentum wheel mounted on said base and having the shaft thereof in frictional contact with the periphery of said first mentioned wheel.

In testimony whereof I affix my signature 85 in presence of two witnesses.

CALVIN C. MILLER.
